DESIGN FOR A LATHE

Edmund J. Lomazzo, Norwalk, Conn.

Application January 17, 1945, Serial No. 117,482

Term of patent 14 years

(Cl. D54—6)

To all whom it may concern:

Be it known that I, Edmund J. Lomazzo, a citizen of the United States, residing at Norwalk, county of Fairfield, and State of Connecticut, have invented a new, original, and ornamental Design for a Lathe, of which the following is a specification, reference being had to the accompanying drawings, forming part thereof.

Figure 1 is a front view of a lathe showing my new design.

Fig. 2 is a top plan view thereof.

Fig. 3 is a back view thereof.

Fig. 4 is an end view thereof looking from the right in Fig. 1, and

Fig. 5 is an end view thereof looking from the left in Fig. 1.

I claim:

The ornamental design for a lathe, as shown.

EDMUND J. LOMAZZO.
